Primary Examiner — Elizabeth Albert

(74) Attorney, Agent, or Firm — Ryan Kromholz & Manion, S.C.

(57) **CLAIM**

We claim the ornamental design for a bottle opener, as shown and described.

DESCRIPTION

FIG. 1 is a top perspective view;
FIG. 2 is a bottom perspective view;
FIG. 3 is a top view;
FIG. 4 is a bottom view;
FIG. 5 is a left side view;
FIG. 6 is a right side view;
FIG. 7 is a front view;
FIG. 8 is a front section view; and,
FIG. 9 is a back view.

The broken lines are included to show a portion of the bottle opener that forms no part of the claimed design.

1 Claim, 2 Drawing Sheets
